CLAIM

The ornamental design for the lazy susan shelf, as shown and described.

DESCRIPTION

FIG. 1 is a perspective view of one embodiment of a lazy susan shelf showing our new design;

FIG. 2 is a top plan view thereof;

FIG. 3 is a bottom plan view thereof;

FIG. 4 is an elevational view thereof as viewed from the bottom of FIG. 2;

FIG. 5 is an elevational view thereof as viewed from the top of FIG. 2;

FIG. 6 is a side elevational view of one side thereof as viewed from the right side of FIG. 2, the other side being a mirror image thereof;

FIG. 7 is an enlarged fragmentary view of a portion of the one embodiment in FIG. 2;

FIG. 8 is a front perspective view of a second embodiment of a lazy susan shelf showing our new design;

FIG. 9 is a bottom view of this second embodiment;

FIG. 10 is a top plan view of this second embodiment;

FIG. 11 is an elevational view of this second embodiment, the other elevational views being alike; and,

FIG. 12 is an enlarged, fragmentary, sectional, elevational view of an outer portion of either the first or second embodiment.
